WEAVING MACHINE

Robert Whewell, Garfield Heights, Ohio, assignor to The Warner & Swasey Company, Cleveland, Ohio, a corporation of Ohio

Filed Oct. 22, 1958, Ser. No. 768,863

9 Claims. (Cl. 139—126)

This invention relates to a weaving machine and more particularly to a weaving machine of the gripper shuttle type.

In weaving machines of the gripper shuttle type the filling or weft thread is taken from a bobbin or package located on the picking side of the machine by means of a feeder device in the picking box and which device transfers the filling or weft to a gripper shuttle which is then picked or fired through the shed. After the pick is completed the feeder device moves forward to a point adjacent the selvage and grips the filling or weft which has been fired through the shed, after which the filling or weft is cut. The feeder device then returns to a position where it inserts the end of the filling or weft extending from the bobbin or package into the next shuttle while the weaving machine is performing the beat up operation.

In the high speed operation of this type of weaving machine approximately half of the cycle time is required for the shuttle to move from the picking box to the receiving box to position the weft or filling in the shed. In order to keep the cycle time as short as possible the feeder device starts moving forward toward the selvage while the picked shuttle is still in flight through the shed. While the feeder device is moving forward as just stated, it is necessary to move the filling thread aside or out of the path of said device to prevent abrasion of the filling thread, after which the filling thread must be repositioned in its normal location so it can be gripped by the feeder device during the cutting operation. An arrangement for displacing and repositioning the filling as well as the feeder device above referred to are disclosed in Pfarrwaller Patent 2,578,205, issued December 11, 1951.

The displacement and repositioning of the filling thread also have been done by a pair of movable or pivoted centering blades located adjacent to the outermost warp thread on the picking side of the machine.

The cutting of the picked filling or weft usually is done by a pair of scissor-like cutting blades, one form of which is disclosed in Moessinger Patent 2,420,380, issued May 13, 1947. The location of the cutting blades or scissors determines the length that the cut end of the picked filling or weft projects beyond the outermost warp on the picking side. In the arrangement utilizing the pivoted centering blades the cutting blades or scissors, heretofore, have been located between the centering blades and the retracted position of the feeder device and hence the projecting cut end of the picked filling or weft is of substantial length and in most instances is longer than is necessary for the subsequent operations to be performed thereon.

An object of the present invention is to provide in a weaving machine of the gripper shuttle type a mechanism such that the centering and displacement of the picked filling or weft to prevent abrasion thereof by the feeder device as it moves forward and the cutting of said filling or weft are performed by a dual purpose unit and

2

this has the advantage that the cut end of the picked filling or weft on the picking side can be cut at a point closer to the outermost warp thread than heretofore has been the case, thus shortening the cut ends of the fillings or wefts on such side of the woven fabric.

The usual cutting blades or scissors do not function always satisfactorily in cutting weft or filling threads stiffer than yarn threads as, for instance, in cutting wire or heavy paper threads when the weaving machine is used to weave wire cloth or sacking material. If the filling is not cut cleanly and completely at the proper time in the cycle there may result a jam which will stop the machine and require the operator to clear the obstruction.

Another object of the invention is to provide in a gripper shuttle type weaving machine a filling or weft cutting mechanism which functions efficiently and satisfactorily on various kinds of filling or weft threads, that is on stiff filling materials such as wire or paper as well as on the usual filling threads of wool, cotton and other similar fibers.

Another object of the invention is to provide a filling centering and cutting mechanism for a gripper shuttle type weaving machine wherein one of the pivoted centering blades performs a dual function and acts as one of the cutting elements of the mechanism.

A further object of the invention is to provide a gripper shuttle type weaving machine an improved filling centering and cutting mechanism embodying fewer moving parts, of simple and inexpensive construction and requiring less critical adjustment for satisfactory operation than has heretofore been available in machines of this type.

Further and additional objects and advantages not hereinabove specified will become apparent hereinafter during the description of an embodiment of the invention which is to follow and which embodiment is shown in the accompanying drawings forming part of this specification and wherein,

Fig. 1 is a sectional view through a weaving machine of the gripper shuttle type which embodies the invention and is taken inwardly of but looking toward the picking box of the machine.

Fig. 2 is a horizontal sectional view through the picking box of the machine shown in Fig. 1 and is taken substantially on line 2—2 of Fig. 1 looking in the direction of the arrows.

Fig. 3 is a view partly in vertical section and partly in side elevation and is taken on or from line 3—3 of Fig. 2 looking in the direction of the arrows.

Fig. 4 is a detached elevational view of the unit constituting the centering blades and cutter bar shown in Fig. 3 but on a larger scale, the centering blades and cutter bar being indicated in Fig. 3 in their most open or retracted position while in Fig. 4 the centering blades are shown in the closed position they occupy when displacing the filling thread from its normal position, and

Fig. 5 is a view similar to Fig. 4 but indicates the relationship of the parts after the closed centering blades have moved to center the filling and the cutter bar has moved to cutting position.

The general organization and the usual constituent elements or operative parts of a weaving machine of the gripper shuttle type, such as disclosed in Fig. 1, are well known in the art and are illustrated and described in Fisher Patent 2,841,186, issued July 1, 1958. Consequently it will not be necessary to give a detailed description of all of the operative parts or elements of the machine but a brief description only should suffice.

It will also be understood that although Fig. 1 illustrates plainly the picking side of the weaving machine, the counterpart of many of the operative elements illus-

trated are to be found likewise on the receiving box side.

The weaving machine shown has side frame members 10 on both the picking and receiving box sides of the machine and these members are interconnected by cross beam members 11 and 12. The side frame members 10 also support the warp beam 13, the breast beam 14, the take-up roll 15 as well as additional elements of the machine hereinafter referred to as will be well understood in the art.

The warp beam 13 is rotatably supported on brackets 16 carried by the cross beam members 11 and 12 and supported at their outer undersides by foot members 16a. The warp beam 13 has fixed to it adjacent one end thereof a gear 17 which meshes with a let-off gear 18 on a shaft 18a that is journaled in the frame members 10 and is controlled by a suitable let-off mechanism, not shown, but well understood in the art. The warp elements or threads 19 are wound on the warp beam 13 and are let off therefrom to pass over the whip roll 20 and through a drop wire detecting mechanism 21. The warp threads pass from the detecting mechanism through the heddles 22 to which they are suitably connected and then through a beat up reed mechanism 23 on the opposite side of the shed from the detecting mechanism 21. The warp threads 19 with the inserted and beat up weft or filling threads interwoven therewith pass as woven cloth over the breast beam 14 around cloth roll 24 and sand or pressure roll 25 to the cloth take-up roll 15, all as is well understood in the art. The shed 26 is formed by the raising and lowering of selected warp threads 19 by the heddles 22 and the latter are raised and lowered in predetermined manner by a shedding mechanism indicated generally at 27 but well understood in the art.

The beat up reed 23 is carried by the lay bar 28 which also carries the shuttle guide 29. The lay bar 28 is operatively connected to a lay shaft 30 that is driven from the main shaft 31 by operative connections housed in the drive box 32. The different operative elements or units of the weaving machine are driven from the main shaft 31 which, in turn, is operatively connected through a clutch mechanism to a motor, not shown, and located on the frame member 10 at the receiving box side of the machine. The main drive shaft 31 extends into the picking box 33 and, as will be understood, actuates the picking box cam shaft 34 through a suitable gear driving connection therewith.

The picking box cam shaft 34 is operatively connected to a shaft 35 which extends into the receiving box of the weaving machine and is operatively connected to a receiving box cam shaft, not shown, but well known in the art. The picking box mechanism and the receiving box mechanism thus are driven and operated in synchronization to provide for the necessary accurate timing required for the efficient operation of the weaving machine.

It will be understood that various cams, not illustrated herein, are mounted on the picking box cam shaft 34 to actuate and control the feeding and picking mechanisms contained in the picking box.

The cams on the picking box cam shaft 34 above referred to include a pair of cams 36 and 37 (see Figs. 2 and 3) which function to actuate the centering blades and the cutter bar of the positioning and cutting unit embodying the invention as will clearly become apparent during the description that follows.

A lever 42 is rockably mounted in the picking box on a pivot 43 and the lower end of said lever is provided with divergent arms, the free ends of which rotatably mount roller type cam followers 38 and 39. The cam followers 38 and 39 bear on the cam contoured surfaces, respectively, of the cams 36 and 37 and rotation of these cams with the shaft 34 acts to rock or oscillate the lever 42 on the pivot 43 and in properly timed movements. The pivot 43 for the lever 42 is carried by a pivot block 44 which is slidable on the upper surface of a web wall 45 of the picking box housing. The pivot block 44 is pro-

vided with a tongue 46 on its side that has sliding engagement in a groove 47 formed on the side wall 48 of the picking box housing (see Fig. 2). Thus the pivot block 44 will have guided linear movement limited in one direction by a stop block 52 secured to the web wall 45 and held against lateral displacement by a gib 49 secured to the web wall 45.

The pivot block 44 at its end remote to the stop block is recessed to engage one end of a compression spring 50, 10 the opposite end of which fits within an adjustable plug 53 that is screwed into the front wall 54 of the picking box. The plug 53 can be adjusted to cause the spring 50 to exert a desired spring load on the pivot block 44.

The arrangement just described enables the pivot block 15 44 to move against the spring load to shift the pivot 43 of the lever 42 to provide an overload release to prevent jamming and possible breakage of the mechanism should the necessity arise.

The upper free end of the lever 42 is pivotally connected by a pivot pin 55 to one end of a link bar 56. The link bar 56 has its other end pivotally connected by a pivot pin 58 to an arm 57. The arm 57 is fixed to a rocker shaft 59 supported in suitable bearings in the picking box 33; the arm 57 being illustrated in this 25 instance as having a split portion which straddles and is clamped to the rocker shaft 59. The rocker shaft 59 extends through the side wall 48 and into a recess 60 in the outer side of said side wall. A gear sector 61 is fixed in any suitable way on the end of the rocker shaft 59 in the recess 60 to have rocking movement with said shaft. This gear sector 61 meshes with the rack portion of a bar 62 that slides vertically in a guide groove 63 formed in the side wall 48. Suitable cover plates 64 and 65 secured to the picking box retain the gear sector 61 and bar 62 in the recess 60 and groove 63 (see Figs. 2 and 3).

It will be seen that rotation of the shaft 34 as the machine operates acts through the cams 36 and 37 fixed thereto to oscillate the lever 42 about its pivot 43 and thus to oscillate the link bar 56 and through the arm 57 cause rocking oscillation of the rocker shaft 59. This 40 rocking oscillation of the rocker shaft 59 effects, through the gear sector 61 and the rack portion of the bar 62, vertical reciprocating movements of said bar in the groove 63 and these movements are in timed relationship to the other operative parts of the weaving machine as will be 45 well understood.

The path of the shuttles as they are picked through the shed is indicated at 66 in Fig. 3 and the shuttles are confined to this path by guides 67 and 68 and a co-operating groove in the housing 69 until the shuttles enter 50 the shed.

As previously stated, the displacement and repositioning of the filling threads carried through the shed by the shuttles are effected by a pair of movable or pivoted centering blades located adjacent to the outermost warp 55 thread on the picking side of the machine. These centering blades are indicated in the drawings at 70 and 71 and the lower ends of the blades 70 and 71 are pivotally mounted on a common pivot pin 72 that is carried by the fixed plate 73 secured to the picking box 33. The 60 upper ends of the centering blades 70 and 71 when said blades are in open or spread apart position lie on opposite sides of the shuttle path 66 as clearly indicated in Fig. 3. The construction of the upper ends of the blades 70 and 71 will be described in detail hereinafter.

A cutter arm 74 has one end secured by suitable clamping means 75 to the vertically reciprocating bar 62 so as to project from said bar at right angles thereto. The outer or free end of the cutter arm 74 is of wider dimension in the vertical direction than the remainder 70 of said cutter bar and the side plane of the outer end of the cutter arm 74 lies adjacent to and parallel with the centering blades 70 and 71 and in contact with the side of the centering blade 71.

The outer end of the cutter arm 74 mounts a pin 76

which extends into cam grooves 77 and 78 formed, respectively, in the centering blades 70 and 71. The centering blades are retained in proper operative position relative to the pin 76 by suitable resilient retaining means such as a snap ring on one end of the pin and a Belleville washer 79 on the other end thereof and which maintains the desired and proper contact pressure between the centering blade 71 and the outer end of the cutter arm 74 for a purpose later to become apparent.

It will be seen that the centering blades 70 and 71 are actuated by the vertical reciprocating movements of the cutter arm 74 with the bar 62. When the bar 62 is at its lowermost position as indicated in Fig. 3, the pin 76 of the cutter arm 74 is located in the lower ends of the cam slots 77 and 78 and the centering blades are in their most spread apart position.

When the oscillating movement of the lever 42 and link bar 56 rocks shaft 59 in a direction such that the gear sector 61 causes vertical upward movement of the bar 62 the pin 76 carried by the cutter arm 74 travels upwardly in the cam slots 77 and 78 of the centering blades. When said pin 76 is intermediate the lower and upper ends of said cam slots, as indicated in Fig. 4, the centering blades 70 and 71 are in closed relationship and both have been moved to a position wherein the filling thread passing between the centering blades is displaced from its normal position in alignment with the path 66 of the shuttles. The continued upward movement of the bar 62 derived from the gear sector 61 and the oscillating lever 42 moves the pin 76 carried by the cutter arm 74 from the position shown in Fig. 4 to the broken line position as indicated in Fig. 5. In this broken line position of the pin 76, the centering blades are still closed but said blades both have been moved from the displaced position of Fig. 4 to center the filling with respect to the shuttle path 66. The continued upward movement of the cutter arm moves the pin 76 idly in the straight portions of the slots 77 and 78 at the upper ends thereof from the broken line position of Fig. 5 to the full line pin position thereof.

The outer or free end of the cutter arm 74 on its upper edge has fixed thereto a cutter block 80. This cutter block 80 may be formed integrally with the cutter arm 74, but preferably it is in the form of an insert of hard material such as tungsten carbide that is brazed or welded or otherwise secured to the upper edge of the cutter arm. The cutter block 80 is movable against the outer surface of the centering blade 71 with a predetermined pressure produced by the Belleville washer 79 and when the parts are in the position shown in Fig. 5, said cutter block 80 has cut the filling thread due to the shearing action between it and a portion of the blade 71 later referred to.

The upper end of the centering blade 70 is provided in an edge thereof with a cutout 81 while the opposite side edge of the centering blade 71 is provided with a slot 82. The filling thread when the centering blades 70 and 71 are in the position shown in Fig. 4 is held in the slot 82 of the blade 71 by the inner edge portion of the cutout 81 in the centering blade 70 and thus the movement of said centering blades from the center line 83 to the position shown in Fig. 4 acts to displace the filling thread out of alignment with the shuttle path 66 to a position wherein the feeder device such as disclosed in the previously mentioned Pfarrwaller Patent 2,578,205 will not cause abrasion of the filling thread as said device moves forward toward the selvage while the picked shuttle is still in flight through the shed.

The resume of the operation of the centering blade and cutter mechanism described herein in conjunction with the operation of the weaving machine will now be set forth. When a shuttle is starting its picking flight into the shed the pin 76 of the cutter arm 74 is at the lower end of the cam slots 77 and 78 in the centering blades and the latter are in their spread apart relationship shown

in Fig. 3 to allow the shuttle and the filling to pass therebetween. After the shuttle has started through the shed 26 the cams 36 and 37 on the shaft 34 start to raise the bar 62 through the operative connections between the bar 62 and said cams as previously described. This movement of the bar 62 upwardly raises the cutter arm 74 and the pin 76 to the position shown in Fig. 4. The pin 76 first moves upwardly through the lower straight portions of the cam slots or tracks 77 and 78 without moving the centering blades and then moves the centering blades to closed position relative to each other and to a mutually displaced position relative to the center line 83 to displace the filling as previously described. When this point in the cycle of operation is reached there is a predetermined dwell in the movement of the bar 62, cutter arm 74 and centering blades 70 and 71 due to dwell portions on the cams 36 and 37. When the picked shuttle has reached the receiving box and its movement has been stopped a tensioning mechanism known in the art tensions the filling thread. At this time the cams 36 and 37 cause the raising of the bar 62 and cutter arm 74 from the position shown in Fig. 4 upwardly, with the result that the centering blades 70 and 71 are centered relative to the center line 83 and the filling is again in alignment with the shuttle path 66, while the pin 76 is in straight upper portions of the cam slots 77 and 78 of the centering blades.

The feeder device previously referred to is now gripping the filling and the cams 36 and 37 cause further upward movement of the cutter arm 74 and of the pin 76 in the straight upper portions of the cam slots during which the cutter block 80 moves to the position shown in Fig. 5 and cuts the filling because of a shearing action between the cutter block 80 and the upper edge of the slot 82 in the centering blade 71. After the filling has been cut the cams 36 and 37 act to effect lowering of the cutter arm 74 to move the pin 76 from the position shown in Fig. 5 to the position shown in Fig. 3, at which time said pin is in the lower ends of the cam slots and the centering blades are in spread apart position so that a shuttle may pass therebetween on the next pick.

It will be noted that the filling is cut adjacent the outer surface of the centering blade 71 and said surface is closely adjacent to the outermost warp thread. Consequently the cut end of the filling projects beyond the outermost warp thread a minimum distance, namely, a distance equal to the thickness of the cutter block 80 and the clearance between the cutter block and the warp thread. As stated, the filling is held during the cutting action and, therefore, the cut filling is not deflected by the centering blades or other elements during beat up of the filling. In view of the non-deflection of the cut end of the filling the mechanism disclosed herein is particularly adaptable to a weaving machine operating on fillings of wire or other relatively stiff material.

The upper surface of the cutter block 80 and the upper edge of slot 82 in centering blade 71 which form the actual cooperating shearing edges may be arranged parallel during the cutting operation insofar as some filling materials are concerned. However, with other materials these cooperating cutting or shearing edges function more efficiently if they meet at an angle during the shearing or cutting operation.

The adaptation of the shearing or cutting edges of the block 80 and of the slot 82 for the filling material last mentioned, can readily be effected either by changing the configuration of the slot edge or by angularly disposing the shearing edge of cutter block 80.

Although a preferred form of the invention has been illustrated and described herein various modifications and adaptations may be made within the scope of the invention as defined in the claims.

Having thus described my invention what I claim is:

1. In a weaving machine of the gripper shuttle type having a picking box and an actuating shaft in said box,

movable centering means through which extends the filling thread and which is located on the side of the machine having said picking box to displace said thread laterally from a normal position and then move said thread laterally to normal position, movable cutting means for the thread in movable contact with said centering means and located intermediate said centering means and the outermost warp on the picking side, said centering means and said cutting means having cooperating thread shearing portions, actuating means operatively interconnecting said centering means and said cutting means whereby movement of said cutting means first moves said centering means to thread displaced position and then to thread normal position, after which said centering means remains stationary and said cutting means moves relative thereto to cause said cooperating portions to shear the thread, and means operatively interconnecting said actuating shaft with said cutting means to move the latter.

2. In a weaving machine as defined in claim 1 and wherein said centering means is pivoted to swing about a fixed axis while said cutting means is reciprocable longitudinally of said centering means in a path transverse to said axis.

3. In a weaving machine as defined in claim 1 wherein said centering means includes a pair of centering blades pivotally mounted upon a common pivot while said cutting means reciprocates longitudinally of said blades and transversely of said pivot.

4. In a weaving machine as defined in claim 3 and wherein the centering blade of said pair of centering blades which is in contact with said cutting means is provided with a filling receiving slot while the cooperating portions for shearing the filling carried by the centering means and the cutting means are located on the edge of said slot and on the upper edge of said cutting means, said other centering blade of the centering means being provided with a cutout cooperating with said slot to retain the filling in said slot during movement of said centering blades to and from filling displaced position.

5. In a weaving machine as defined in claim 4 and wherein said actuating means operatively interconnecting said centering means and said cutting means includes longitudinally extending cooperating cam slots in said centering blades, and a pin carried by said cutting means and extending into said slots.

6. In a weaving machine of the gripper shuttle type having a picking box and an actuating shaft in said box, movable centering means through which extends the filling and which is located on the side of the machine having said picking box to displace said filling laterally

from a normal position and then move said filling laterally to normal position, movable cutting means for the filling in movable contact with said centering means and located intermediate said centering means and the outermost warp on the picking side, said centering means and said cutting means having cooperating thread shearing portions, actuating means operatively interconnecting said centering means and said cutting means whereby movement of said cutting means first moves said centering means to filling displaced position and then to filling normal position after which said centering means remains stationary and said cutting means moves relative thereto to cause said cooperating portions to shear the thread, said actuating means including cam slots in said centering means and a pin carried by said cutting means and extending into said cam slots, and means operatively interconnecting said actuating shaft with said cutting means to move the latter.

7. In a weaving machine as defined in claim 6 and wherein said cam slots of said actuating means have a straight end portion and inwardly of said straight portion an inclined portion, the movement of the pin carried by the cutting means in said straight portion of said cam slots producing no movement of said centering means while the movement of said pin in said inclined portion of said cam slots produces movement of said centering means to move the filling to and from normal position.

8. In a weaving machine as defined in claim 6 wherein the means operatively interconnecting said actuating shaft with said cutting means includes cams on said actuating shaft, a movable bar carried by the picking box and connected to said cutting means, and means operatively interconnecting said bar and said cams on said actuating shaft.

9. In a weaving machine as defined in claim 8 wherein the means operatively interconnecting said bar and said cams includes a lever rockably supported in said picking box and provided at one end with cam followers engaging said cams and at the other end pivotally connected to one end of a link bar, the opposite end of which link bar is pivotally connected to an arm fixed on a rock shaft carried by the picking housing, said rock shaft mounting a rack segment while said first mentioned bar is provided with a rack intermeshing with said segment.
